[57] CLAIM

The ornamental design for a child's educational calendar, as shown and described.

DESCRIPTION

FIG. 1 is a front perspective view of a child's educational calendar showing my new design;

FIG. 2 is a front elevational view thereof;

FIG. 3 is a side elevational view thereof, the undisclosed side being a mirror image;

FIG. 4 is a rear elevational view thereof;

FIG. 5 is a top plan view thereof; and,

FIG. 6 is a bottom plan view of my design.

It is understood that FIG. 1 is shown with all indicia removed for clarity of illustration only.

FIG.1

FIG.2

FIG.3

FIG.4

FIG.5
